UNITED STATES PATENT OFFICE.

WILLIAM PICKUP, OF PENDLETON, ENGLAND.

ROTARY PHOTOGRAVURE-PRINTING MACHINE.

1,399,987.

Specification of Letters Patent. Patented Dec. 13, 1921.

Application filed October 25, 1919. Serial No. 333,148.

To all whom it may concern:

Be it known that I, WILLIAM PICKUP, a subject of the King of Great Britain, residing at Pendleton, in the county of Lancaster, 5 England, have invented certain useful Improvements in Rotary Photogravure-Printing Machines, of which the following is a specification.

This invention relates to that type of rotary photogravure printing machines in which an etched or engraved copper cylinder is employed for printing pictures or reading matter on paper or other material in sheet or reel form, in one or more colors 15 by passing same once, twice or more times through the machine.

This invention has for its object to provide said type of machines with simple and effective means which permit of printing 20 sheets of paper or other material in such a manner that the second and subsequent printing will be in accurate register.

I attain the recited object by the mechanism illustrated in the accompanying sheet 25 of drawing.

Referring to the drawing, the printing cylinder *a* is as usually mounted in two bearings *b*, rendered slightly vertically movable in guides *c* and above said cylinder is mounted also in suitable bearings, an impression roller *e* between which and the cylinder *a* the paper *f* is fed to take the etching or engraving from the printing roller *a*.

Above the impression roller *e*, a vertically 35 adjustable pressure roller *g* is as usually employed to run in contact therewith.

The printing roller *a* revolves continuously and drops slightly every alternate revolution, which provides time for inserting 40 the paper *f* in sheet form between cylinder *a* and roller *e*, and dispenses with the ordinary feed grippers hitherto necessary.

h is the board or table by which the sheets of paper are fed. This board or table is provided with wheels *i* and rendered horizontally reciprocable on rails *k*.

The feed board or table *h* is provided with the usual lay guides *l* rendered adjustable thereon.

50 The printing cylinder *a* is raised and dropped by means of cams *m* secured on each end of the driving shaft *n* and acting upon links *o* vertically slidable in the frame *p* of the machine and with upper ends pivoted to

the bearings *b*. The driving shaft *n* has secured thereto the cams *m* geared up with the printing cylinder *a* by means of a train of wheels *q*, *r*, *s*, *t*, so proportioned as to cause the cams *m* to make one revolution while the printing cylinder makes two revolutions. 55

The wheel *s* remaining vertical stationary, permits of lowering and raising the printing roller *a* without coming in either position out of gear with the wheel *s*, which insures a positive drive. 60

To get the accurate printing register, a lever mechanism is employed, worked from the cam shaft *n* by means of the cam *u*, adapted to move the board or table *h* carrying the sheet *f* toward the printing cylinder 70 *a* the required distance, the front edge of the sheet being placed slightly past the vertical center line of the printing cylinder *a*.

The said lever mechanism comprises in the present instance, a lever *v* having two arms 75 *w*, *x* of which *w* is acted upon by the cam *u* while the other arm *x* by means of a connecting rod is pivoted to the feed board table *h* and adapted to reciprocate same.

The cams *m* are timed at this point to lift 80 the printing cylinder *a* against the impression cylinder *e*. The sheet is printed on the under side and as it leaves the printing cylinder *a* and impression roller *e*, passes between two steel guides *z*, 2 and is then received by a pair of endless traveling tapes 85 3 which turn the sheet over ready for delivery on the receiving board or lattice 4.

I claim:—

1. In a rotary photogravure printing machine having a vertically slidable printing cylinder and above same mounted a vertical stationary impression roller, a spur wheel secured on the shaft of said printing cylinder, a driving shaft mounted below in a vertical line with said cylinder, a spur wheel secured to said driving shaft, a spur wheel mounted vertical stationary in a horizontal line and in gear with the spur wheel on the shaft of said cylinder and an intermediate spur wheel 95 mounted between and in gear with said vertical stationary wheel and the spur wheel on said driving shaft, for the purpose specified. 100

2. In a rotary photogravure printing machine, as claimed in claim 1, a horizontally 105 movable feed table and means for intermittently actuating same from said driving shaft, for the purpose specified.

3. A rotary photogravure printing machine as claimed in claim 2, comprising a cam secured to said driving shaft, an angular lever fulcrumed with one end in direct contact with said cam with other end pivotally connected with the said paper feed table, for the purpose specified.

Signed at Manchester, in the county of Lancaster, this 2nd day of October, 1919.

WM. PICKUP.
